CLAIM

The ornamental design for a battery grid, as shown and described.

DESCRIPTION

FIG. 1 is front elevational view of a battery grid showing our new design, the rear being a mirror image thereof;

FIG. 2 is a top plan view thereof;

FIG. 3 is a right side elevational view thereof;

FIG. 4 is an enlarged cross-sectional view thereof as taken along line 4—4 of FIG. 1;

FIG. 5 is an enlarged cross-sectional view thereof as taken along line 5—5 of FIG. 1;

FIG. 6 is an enlarged, fragmentary bottom plan view thereof;

FIG. 7 is a greatly enlarged view of the portion of the front indicated by the broken line square in FIG. 1; and FIG. 8 is a greatly enlarged view of the portion of the front indicated by broken line square 8 in FIG. 1.

The grid is fragmentarily shown in FIG. 6 for convenience of illustration.
